JEWELRY RACK

Filed April 18, 1951

Inventor

Arthur O. Talmadge

UNITED STATES PATENT OFFICE

165,404

JEWELRY RACK

Arthur O. Talmadge, Atlanta, Ga.

Application April 18, 1951, Serial No. 14,887

Term of patent 14 years

(Cl. D80—9)

To all whom it may concern:

Be it known that I, Arthur O. Talmadge, a citizen of the United States, residing at Atlanta, in the county of Fulton and State of Georgia, have invented a new, original, and ornamental Design for Jewelry Racks, of which the following is a specification, reference being had to the accompanying drawing, forming part thereof.

The figure is a perspective view of a jewelry rack, showing my new design.

I claim:

The ornamental design for a jewelry rack, as shown.

ARTHUR O. TALMADGE.
